METHOD AND APPARATUS FOR
HANDLING MATERIALS

George H. Pride, New York, N. Y.

Application January 31, 1935, Serial No. 4,255

26 Claims. (CL 214—65)

This invention relates to improvements in apparatus for handling materials, and, although it may be adapted for the handling of a wide variety of materials, it is of particular utility as applied to the handling of stacked loads.

Materials of the character referred to, such, for example, as stacks of paper, cardboard, or sheet metal, have commonly been handled in the past by being placed upon conventional carrying skids at the production source and being transported from place to place on such skids until the material reached a destination where it was to be used in manufacture, sold, or otherwise disposed of. The skids were thereupon ordinarily discarded.

The skids referred to comprise comparatively heavy, rigid platforms of sufficient strength to support a load, and have cross members on their under sides which are adapted to rest on a floor. These cross members keep the platform spaced from the floor, thus affording a space into which a lifting element of a conventional lift-truck may be placed and the skid and load lifted from the floor.

These skids, which are ordinarily used once and then discarded, are usually constructed of wood and are quite expensive. In some instances attempts have been made to minimize this expense by repeated use of the skids, but this practice is about as objectionable as the evil itself, as other expenses are encountered in keeping records of the whereabouts of the skids and in transporting them back to their place of origin.

In my United States patent, No. 1,973,098, granted September 11, 1934, I disclosed an invention of apparatus for handling materials which eliminates the use of such skids, said apparatus consisting chiefly of an inexpensive, flexible, load-supporting platen tensioned in a suitable frame which is adapted to be moved from one place to another with the load. The platen may be disconnected from the frame at will, and as both the shippers and consignees have similar frames, it is only necessary that the inexpensive platen accompany the load in transit.

The present invention, generally speaking, has for its chief object an improvement in the device described in such patent whereby the devices may be better manipulated when the materials are being handled in small spaces or being placed in or removed from a small corner of a room or freight car.

Another object of the invention is to provide a frame of the general character referred to which may be moved horizontally about the load of

material into position, as distinguished from lowering the frame into position around the load.

Another object of the invention is to provide a frame of the general character referred to which may be operated entirely from one end thereof, thus permitting its operation in very small spaces or corners.

A further object of the invention is to provide a frame of the general character referred to which may be operated to rapidly pick up a load from the floor and rapidly release the load after it has been moved.

A still further object of the invention is to provide a frame of the general character referred to, which, by holding the platen therein under a uniform tension, will handle heavier loads than could be handled if the tension were not uniform.

Other objects will become apparent upon a reading of the following specification.

I achieve these objects by providing a mobile U-shaped frame which may be rolled, with the open end foremost, to a position substantially surrounding a load. The frame has means for attaching it under uniform tension to a platen which is underneath the load and also means for lifting the load off the floor. The entire operation of the frame may be handled from its closed end, thereby permitting the use of the frame even in the smallest corners encountered in practice.

My present invention is defined in the appended claims, and is hereinafter described in detail. In this description reference is made to the accompanying drawings, in which,—

Figure 1 is a plan view of the apparatus, the position of a load being indicated in broken lines.

Fig. 2 is a side elevation, partly broken away, of one of the two substantially similar opposite sides.

Fig. 3 is an end elevation of the apparatus as viewed from the right of Fig. 1, this end of the apparatus being hereinafter referred to as the open end.

Fig. 4 is an enlarged vertical cross-section on the line 4—4 in Fig. 1, portions of the remote end of the apparatus being omitted for clearness.

Fig. 5 is an enlarged vertical cross-section of one of the sides of the apparatus on line 5—5 of Fig. 1.

Fig. 6 is an end elevation, partly broken away, as viewed from the left of Fig. 1, but showing modifications in several parts of the apparatus, this end of the apparatus being hereinafter referred to as the operating or closed end.

Fig. 7 is an elevation of one of the sides, further

illustrating a modified clamp-actuating mechanism which is partly illustrated in Fig. 6.

Fig. 8 is a plan view of the clamp-actuating mechanism illustrated in Fig. 7.

5 Fig. 9 is a plan view of a positioning device for securing correct alignment of the platen with clamping members on the frame.

Fig. 10 is a perspective view of a platen suitable for use as a part of the apparatus.

10 Fig. 11 is an elevation of one of the two substantially similar opposite sides illustrated in Fig. 2, as viewed from within the frame.

The platen

15 Referring to Fig. 1, the apparatus comprises a load-supporting platen A, which is preferably flexible, secured in a horizontal position within a mobile and adjustable conveying frame B. The form of the platen A which is preferred, is shown 20 in detail in Fig. 10, and comprises a series of similar and substantially parallel, thin, flexible steel strips 11, of high tensile strength, held together as a unitary structure by being cemented or otherwise secured between mats 12, 12', which 25 may be of cardboard or other thin material having sufficient strength to maintain the platen as a unit until it has been placed into service. The end portions of the strips 11 are turned upwardly at right angles to the main portion of the platen, 30 forming a series of upturned tabs 13 on each side of the platen. In the platen as thus assembled the steel strips 11 all lie in the same horizontal plane, while the tabs 13 on either side of the platen are all in the same vertical plane and the planes of the tabs on the two sides of the 35 platen are substantially parallel. Ordinarily the strips 11 may be of commercial steel strip or "hoop iron" such as is commonly used for baling purposes. The precise characteristics of the steel 40 strips depend, of course, on the size and weight of the load, the prime consideration being that they shall have sufficient tensile strength to carry the load when tensioned in the frame.

The tabs 13 of the platen are so disposed that 45 when the frame is moved into position around the base of the load and then lowered over the said tabs, they will extend upwardly between clamping members on the frame in position to be secured thereto when the clamping members 50 are closed.

Other forms of platen may be employed, and particularly those which have upwardly-extending members corresponding to the tabs 13, which are adapted for connection to the frame.

55 The frame

The main body of the conveying frame B is substantially U-shaped and consists of two similar horizontal side members 14, preferably of channel iron, connected at corresponding ends by an adjustable end section 15 extending across the closed end of the frame. This end section 15 is rigidly secured to the side members by bolts 16 which extend through web 14' of the side member and are threaded into the end section 15. A reinforcing strap 17 may be used to reinforce the web 14' at this point, as shown in Fig. 2.

The frame B is made mobile by being mounted on non-swiveling casters 18 on the side members 70 14 at the open end of the frame and on swiveling casters 18' on the adjustable end section 15 at the closed end of the frame.

75 The frame elevating means

75 The mounting of these casters is such that the

main body of the frame may be raised or lowered at will to pick up or release a load. These casters are secured to the lower ends of four vertical screw lifting elements 19 which extend through suitable vertical bores in brackets 20, which are bolted or otherwise rigidly secured to the main body of the conveying frame B.

These screw lifting elements 19 are adapted to move vertically within the brackets 20, but are keyed against rotation therein by keys 21 in the 10 brackets, which keys slide in vertical grooves 22 in the screw lifting elements. The vertical movement of the screw lifting elements 19 in the brackets 20, and the consequent raising or lowering of the frame, is governed by the rotation of 15 internally threaded sprocket wheels 23 mounted within the brackets and being rotatable on the vertical screw lifting elements. Although free to be rotated as desired, the sprocket wheels 23 are held against vertical movement relative to 20 the brackets 20 by being disposed between and restricted by the parallel faces of slots 24 in said brackets. Thus the rotation of the sprocket wheels 23 causes vertical motion of the vertical screw lifting elements 19 in the brackets 20, and 25 the frame in consequence is raised or lowered as desired.

The operation of these sprocket wheels 23 for controlling the height of the frame is accomplished by a sprocket chain transmission arrangement which may be operated from the closed or operating end of the frame. Bevel ring gears 26 are mounted on cross shafts 33 at each corner of the operating end of the frame to mesh with and drive bevel pinions 27 together with chain driving sprocket wheels 28, the said pinions and sprocket wheels on each side of the frame being keyed to a common vertical spindle 29, as best shown in Fig. 2. The rotation of the chain driving sprocket wheels is transmitted to the driven 40 sprocket wheels 23 by sprocket chains 30 running therebetween. These chains may be enclosed and supported, if desired, within sheet metal covers 31 mounted on the frame.

In the structure illustrated, the bevel ring gears 45 26 on each side of the frame are arranged to be independently operated, reversible ratchet wrenches 25 being provided to turn the cross shafts 33 and the bevel ring gears which rotate therewith. These ratchet wrenches may be quickly 50 adjusted to turn the bevel ring gears in either direction to accomplish the raising or lowering of the frame. Obviously the ring gears may be power-driven, if desired. They may also be arranged to be operated in unison by mounting them on a common cross shaft 32, as shown in Fig. 6, thus increasing the speed of operation of the apparatus and keeping the frame in a horizontal position at all times. It will be seen that under any of the arrangements referred to, the raising or lowering 55 of the frame may be accomplished by an operator standing at the closed end of the frame.

The clamping mechanism

An important feature of this invention resides 65 in the mechanism for clamping the platen to the frame. As heretofore stated, the upturned tabs 13 on each side of the platen are adapted to extend between clamping members carried by the frame, which members, when moved to a closed position, 70 will securely grip the said tabs, whereby to permit the platen, carried within the rigid frame, to carry a load.

It is desirable, in order to fully achieve the objects of this invention, to have clamping mem- 75

bers on each side of the frame which may be simultaneously operated and which will simultaneously grip the tabs 13. As best shown in Figs. 4 and 11, there is provided an elongated clamping bar 34 disposed along the lowermost portion of the inner side of the side member 14. This clamping bar is slidably mounted on guide pins 35 and is adapted to be moved into intimate contact with the adjacent inner surface of said side member, 5 the adjacent surfaces 36 and 37 of the clamping bar and the side member, respectively, serving as cheeks between which the tabs 13 of the platen are engaged. These cheeks, as shown in Figs. 4 and 5, are preferably provided with complementary 10 offset portions 36' and 37' along their length in order to somewhat deform the tabs 13 to afford a more secure gripping action. From the foregoing it will be seen that the side members 14 and the clamping bars 34 form on each side of the frame 15 a single set of clamps adapted to engage a plurality of upturned tabs on the platen.

The movement of the clamping bars 34 from an open position to a closed or clamping position, and vice versa, is effected by providing a plurality 20 of screw means, which, when rotated, will impart the desired motion to the clamping bars. Such screw means are best shown in Figs. 2 and 5. Clamping screws 38 are welded or otherwise non-rotatably secured in the clamping bar 34, the 25 threaded portions of the screws extending through holes in the web 14' of the side members, thence through nuts 39 which are adapted to be rotated either by spur gearing or by a worm, as will be hereinafter explained. The nuts 39 are 30 fixed against lateral movement by being held between the web 14' of the side member and the upturned flange 40 of the angle bracket 41 which is fixed to the lower flange of the channel forming the side member 14, as best shown in Figs. 4 35 and 5. Thus the rotation of the nuts 39 causes the clamping bars 34 to move to or from a clamping position.

A number of these clamping screws are provided on each side of the frame in order to exert 40 powerful clamping pressure along the entire length of the clamping bar 34 and also to uniformly receive the strains to which the clamping 45 bar is subjected when carrying heavy loads.

Means are provided for simultaneously operating 50 all the nuts 39 from the closed end of the apparatus to permit the apparatus to be used in very limited spaces. This may be accomplished by rack-operated spur gearing, as shown in Figs. 1 to 5, inclusive, and Fig. 11, or by a worm gear and 55 worm wheel arrangement, as shown in Figs. 6 to 8, inclusive.

The rack arrangement for operating the clamping mechanism

60 In the spur gear arrangement for operating the clamping screws, the periphery of the nut 39 is provided with spur teeth 39'. For each of the nuts 39 there is provided a driving spur gear 42 meshing with and driving the nut 39. The spur gear 42 is keyed to a short rotatable shaft 43 which extends inwardly through the web 14' of the side member to the inner end of which shaft is keyed a driven pinion 44. An elongated rack 45, having spur teeth 45' on its under side, meshes with the 65 pinions 44 and is adapted to reciprocate horizontally along the inner side of the side member 14. This rack is held in engagement with the pinions 44 by brackets 46, which are bolted or otherwise secured to the inner side of the side member 14. 70 The horizontal movement of the rack, to bring the

clamping members to an open position, is limited by a stop pin 47 which is set into the top of the rack at the end thereof which is adjacent the open end of the frame, said stop pin engaging one of the rack-retaining brackets 46 when the 5 clamping members reach an open position. The movement of the rack to bring the clamping members to a closed position is, of course, limited by the intimate engagement of the clamping members when they reach a closed position, at which time the rack cannot be moved further in the stated direction. This rack, as shown in Figs. 2 and 11, extends to the closed or operating end of the frame. The rack is reciprocated by a rack-driving pinion 48 having teeth 48' engaging and driving a short rack 49 fixed to or integrally formed as a part of the top of the rack 45 at the end thereof, which is at the operating end of the frame. The rack-driving pinion 48 is keyed to a short horizontal spindle 50 which extends to the 10 outer side of the frame and is adapted to be turned by a reversible ratchet wrench 51, which wrench may be operated by a person standing at the closed end of the frame. Separate ratchet wrenches may be provided for use at each side of 15 the frame, or a single ratchet wrench may serve to separately operate the clamping mechanism on either side of the frame. Although I have disclosed means for independently operating the 20 clamping mechanism on each side of the frame by 25 the use of a ratchet wrench, it is obvious that the rack-driving pinions 48 on each side of the frame might be keyed to a common cross shaft, whereby 30 the clamping members on both sides of the frame can be simultaneously operated. It is also 35 clear that this clamping mechanism might be motor-driven, if so desired.

The worm-gear arrangement for operating the clamping mechanism

The modification of the clamp-operating mechanism illustrated in Figs. 6 to 8, inclusive, is similar to the modification of Figs. 1 to 5, inclusive, and Fig. 11 with respect to the arrangement, mounting and functioning of the 45 clamping bar 34 and the screw means for actuating it. In the modification of Figs. 6 to 8, however, the rack and pinion arrangement hereinbefore described is not used but is replaced by a worm gear and worm wheel arrangement 50 which serves to operate clamping screw nuts to move the clamping bar to and from a clamping position. It will be seen by referring to Figs. 6 and 8 that the entire clamp-operating mechanism is carried on the outer side of the frame, 55 thus clearing the inner side of all apparatus except the clamping bar and its mounting.

An elongated worm gear having a plurality 60 of screw portions 142 is mounted on the outer side of the side member 14 of the frame, suitable thrust bearings being provided to receive end-wise thrusts of the worm gear and to minimize end play therein. The worm gear is so mounted that the screw portions 142 engage and drive worm wheels 139 which are internally threaded 65 to rotate on the clamping screws 38, the inner ends of which, as hereinbefore explained, are welded or otherwise non-rotatably fixed to the clamping bar 34. The worm wheels 139 are fixed against lateral movement and therefore 70 the rotation of the worm gear causes the clamping screws 38 to carry the clamping bar 34 to or from a clamping position.

Means are provided for driving the worm gear 75

from the closed or operating end of the frame.

On the worm gear at the said end of the frame is keyed a gear wheel 144 which may be driven by a motor or may be manually rotated, for which latter purpose a handle 146 is provided thereon. In manual operation the clamping bar 34 is brought to a closed position by the direct manual operation of the gear wheel 144. As such means alone may not serve to distort and firmly bind the tabs 13 of the platen between the complementally shaped cheeks of the clamping members, a reduction gear 148 is mounted on the frame in position to mesh with the gear wheel 144. A reversible ratchet wrench 151 is utilized to actuate the reduction gear 148. It may be selectively adjusted to rotate said reduction gear in either direction to clamp or unclamp the platen and it may also be adjusted to permit the reduction gear 148 to rotate freely when the gear wheel 144 is directly manipulated. Thus the clamping bar 34 may be initially moved to what might be termed an incomplete clamping position by the direct rotation of the gear wheel 144, and then the reduction gear 148 operated by the wrench 151 may be used to accomplish the extreme tightening of the clamping members into a complete clamping position whereby the platen may be firmly clamped to the frame to carry its allotted load.

30 The clamp-operating mechanism in this modification is duplicated on each side of the frame and the said mechanisms on both sides of the frame may be connected to work in unison. This clamp-operating mechanism may be operated manually or it may be motor driven. Also, the wrench 151 may be arranged to directly operate the gear wheel 144, eliminating the reduction gear 148.

It will be seen that the clamping mechanism hereinbefore described has the advantage of being entirely operable from the closed or operating end of the apparatus and also that all the upturned tabs 13 along one side of the platen are simultaneously gripped by a single set of clamping members.

Uniform tensioning of the platen

There is, however, another very important advantage derived from this clamping arrangement. It is well known that any load-carrying element is most efficient when the weight of the load is uniformly distributed over its sustaining surface. Thus a tensioned platen of the character described herein will carry a capacity load when the steel strips 11 are under substantially uniform tensions relative to each other and each strip carrying its proportionate share of the load. All other factors being equal, the same platen will fail to support the same capacity load if the several strips 11 are under different relative tensions. In the latter case the strips under greatest tension will be subjected to substantially more than their proportionate share of the load, and upon their capacity being exceeded will break, thus lowering the remaining total capacity of the platen below the weight to be carried and rendering the platen useless for its intended purpose.

The clamping arrangement disclosed herein accomplishes substantially uniform tensioning of the platen and thus enables it to carry capacity loads if desired. Figure 6 shows the frame in an elevated position, the tabs 13 of the platen extending vertically upward between and clear of the side 14 of the frame which serves as an

outer clamping member and the clamping bar 34. When the frame is lowered to the floor the tabs 13 are still clear of the clamping members and as the clamping bar 34 is moved outwardly toward the fixed side member 14 of the frame, the tabs 13 are first held in a loose engagement between the clamping members and such engagement is progressively tightened with the outward movement of the clamping bar 34. When the said clamping bar reaches the heel of the tabs 13, said tabs to some extent resist the further movement of the clamping bar. At this point the tabs are not yet securely gripped and the possible slippage of the several tabs within the clamping members is substantially uniform. Thus, as the clamping bars 34 continue their outward movement to an extreme clamping position, the several strips 11 are uniformly tensioned, whereby the platen is adapted to be loaded to capacity.

Adjustment of the size of the frame

Provision is made for adjusting the width of the frame to permit the handling of loads of different sizes. As best seen in Fig. 6, the closed end of the frame consists chiefly of an inner telescoping member 52 operating within outer telescoping members 53, the outer ends of which are secured to the horizontal side members 14 of the frame.

In order to adjust the width of the frame by causing the telescoping members to move one within the other, a horizontal adjusting screw 54 is provided, the threads on each half of which run in opposite directions. This adjusting screw is threaded into blocks 55 which are mounted on the outer telescoping members 53. It will be seen that when the adjusting screw 54 is rotated in one direction the end of the frame will contract and when it is operated in the other direction the end of the frame will expand.

A bevel pinion and ring gear arrangement is provided for rotating the horizontal screw 54 to accomplish the adjustment of the width of the frame. A bevel ring gear 56 is mounted near the center of the adjusting screw 54 to rotate therewith and is driven by a bevel pinion 57 mounted on a block 58. The adjusting screw 54 passes through the upper portion of the block 58 and the inner telescoping member 52 passes through the lower portion of the block 58 whereby the said block is fixed against rotative movement. The block 58 is held against horizontal movement along the adjusting screw 54, being located between the bevel ring gear 56 and a collar 59, both of which are secured to the adjusting screw as shown.

The upper portion of the bevel pinion 57 is formed to receive a wrench to be used in adjusting the width of the frame. While means are provided for adjusting the width of the frame, it should be observed that in actual practice a frame might be set to carry loads of a certain size which would be standard in that plant or industry, and would seldom, if ever, thereafter require further adjustment.

The open end of the frame, as best shown in Fig. 4, is provided with a cross-bar 60 hinged as at 61, to one side of the frame in such a manner that the bar may swing in a vertical plane between a vertical position as indicated in broken lines and a horizontal position in which it extends to the other side of the frame. In this latter position it may assume a part of the stress imposed upon the frame when a load is being car-

ried. As shown in Fig. 1, this cross-bar may be provided with a sleeve 70 within which the two ends of the said cross-bar telescope and may be adjusted to various desired lengths by pins 71 which may be inserted in registering holes in both the sleeve and the ends of the cross-bar. To secure a finer adjustment of the length of the cross-bar 60, one portion of the bar may be threaded into the sleeve 70 and locked in position by a lock nut, as shown at 72. Thus the length of the cross-bar may be adjusted to conform with the width of the frame.

While the frame is elevated from the floor and being moved to its position about the load, the cross-bar 60 must be held in a vertical position and it should be released when the frame is in place about the load and has been lowered to the floor, so that it will fall into position across the open end of the frame. A rocker arm 62 is pivoted to and extends through the web 14' of the horizontal side member. At the inner end of the rocker arm is a beveled lug 63 which engages a lug 64 on the cross-bar to hold the latter in a vertical position. This bar may be released by the rocking of the rocker arm, which is automatically accomplished when the frame is lowered to the floor by a vertical plunger 65 pivotally connected to the outer end of the rocker arm 62. This plunger passes through a guide 66 and a hole in the bottom flange of the side member of the frame. A spiral compression spring 67 is disposed around the plunger between the guide 66 and a washer 68 which is fixed on the plunger near the lower end thereof. When the frame is in an elevated position with respect to the floor the rocker arm is in a substantially horizontal position, and the lugs 63 and 64 are in engagement whereby the cross-bar 60 is held in a vertical position. When the frame is lowered to the floor after it has been properly placed about the load, the lower end of the plunger 65 contacts with the floor and is pressed upwardly, thus tilting the rocker arm 62 and breaking the engagement of the lugs 63 and 64, whereby the cross-bar 60 is permitted to fall into position across the open end of the frame. A cord or chain 69 extends to the operating end of the frame to permit the cross-bar 60 to again be raised to a vertical position.

50 *Platen aligning device*

It is appreciated that the upturned tabs 13 of the platen may get out of alignment after a load has been placed into a corner of a storeroom or vehicle and that such a tab may not be properly gripped between the clamping members of the frame when at a later time it may be desired to move the load to another position. Experience also shows that after a load has once been carried on the platen and released from the frame the tabs 13 may not stand in a perfectly vertical position. This may be caused by a slight bend being imposed upon the platen along the lower side edges of the load.

65 I provide a device to be used in conjunction with a carrying frame for the purpose of aligning the tabs 13 when it is desired to again pick up the load and move it to another place. A plan of this device is shown in Fig. 9, and it is shown in position in side elevation in Fig. 2, and in end elevation in Fig. 3, in both of which figures the frame is shown elevated from the floor preliminary to being lowered into a position where the clamping bars 34 may be closed upon the tabs 13 of the platen. This device comprises two elongated

5 fingers 73 which are approximately as long as the side of the frame and are loosely hinged together at their ends and adapted to swing horizontally with respect to each other. As best shown in Figs. 2 and 3, the arms of this device have a vertical thickness which is somewhat less than the height of the tabs 13. The lower edges of the free ends of this device are beveled, and rollers 74 are provided which are set into the arms and are adapted to permit the device to be moved easily along the floor and over the horizontally-extending portions 11 of the platen.

10 One of the arms is adapted to pass over the said portions 11 in a position between the tabs 13 of the platen and the side of the load, and the other arm is adapted to pass along the outer sides of the said tabs 13. It will be apparent that this device can readily be moved into place from the side or end of the load to which access may be had. After this positioning device 15 is set in place with the upwardly-extending tabs 13 of the platen extending between the arms thereof the mobile frame is then moved into position about the load, the positioning device serving as a buffer along which the wheels of the 20 casters 18 may be guided while the frame is being moved into position. After the frame has been moved into position the upper ends of the tabs 13 of the platen will extend between the clamping cheeks 36' and 37' and the positioning 25 device may then be withdrawn from the operating end of the frame and the frame lowered into clamping position.

30 It will be obvious that if it is desired to have the elevating mechanism on both sides of the frame operate in unison and/or the clamping mechanisms on both sides of the frame work in unison, the cross members serving to link such mechanisms together may be splined members similar to the cross shaft 32 shown in Fig. 35 40 6, whereby the unity of operation may be maintained when the frame is adjusted at any desired width.

Mode of operation

35 It will be seen that the entire operation of the apparatus may be accomplished by an operator at the closed or operating end thereof. Assuming, for the purpose of illustration, a rather extreme set of circumstances, it might be desired to move a stacked load of sheet metal from 45 50 a confined corner of a storage room to a corner of a railroad freight car.

40 Before the material is stacked in the corner of the storage room, the platen A, of a suitable size, is placed on the floor and the material then 55 placed upon it. The devices for positioning the tabs 13 of the platen are rolled, open ends first, along each side of the load with one arm between the platen tabs and the load and the other arm outside of the platen tabs. The tops 60 of the platen tabs will extend above the positioning devices.

45 The mobile frame B is then raised or lowered so that the sides of the frame will just clear the tops of the positioning devices, this being done by manipulating the ratchet wrenches 55 60 65 70 75. The frame is then rolled, open end first, into a position adjacent the end of the load and the width of the frame adjusted by a suitable rotation of the bevel pinion 51, a corresponding adjustment being made in the length of the cross-bar 60 bridging the open end of the frame. The said cross-bar is then raised and held in a vertical position by the coacting lugs 63 and 64 and the frame is then moved into position about 75

the load, the outer arms of the positioning devices serving as buffers for and being pressed laterally into an aligning position by the casters 18 on the frame.

5 The positioning devices are then withdrawn from under the frame as the upturned tabs 13 of the platen are, at this stage, in position between the clamping members of the frame. The frame is then lowered to the floor and as the 10 lugs 63 and 64 have been disengaged by the contact of the plunger 65 with the floor, the cross-bar 60 falls into position across the open end of the frame.

15 The clamping bars 34 are then moved into clamping engagement with the side members 14 of the frame by the manipulation either of the ratchet wrenches 51 of the first modification or the spur gear 144 of the second modification as hereinbefore explained.

20 The frame with the platen and load is then elevated from the floor and the apparatus with its load is rolled to the corner of the freight car where the load is to be placed. The load is then lowered to the floor of the car, the clamping members opened and the frame, free of the load, elevated clear of the upturned tabs of the platen. The cross-bar 60 is then raised to a vertical position by pulling the chain 69 and the frame thereupon rolled from its position about 30 the load.

35 When the load reaches its destination, the consignee, having a similar frame, can readily unload the material and move it from place to place as desired.

40 It will be understood that the invention is not limited to the particular constructions described herein and illustrated in the accompanying drawings. Obviously the apparatus is not limited to a U-shaped frame, as many of the features 45 hereinbefore described might be advantageously used in complete frames which might be lowered or otherwise placed in position about a load. The apparatus and the several parts thereof may be variously modified without departing from the spirit of the invention as set forth in the following claims.

What I claim is:

1. Apparatus for handling materials, comprising a platen, a frame adapted to be placed substantially around a load and means for fastening the platen to the frame, said fastening means comprising clamping members on opposite sides of the frame adapted to uniformly engage the corresponding opposite sides of the platen along substantially its entire length, and means for moving the clamping members outwardly into clamping relationship with the platen, the said fastening means being adapted to yieldingly engage the platen during the period of the movement of the clamping members into clamping relationship, whereby to establish a substantially uniform tension throughout the platen.

65 2. In the combination of apparatus for handling materials, comprising a platen, a frame adapted to be placed substantially around a load, and clamping members carried by the frame for clamping a side of the platen to the corresponding side of the frame, screw means and operating mechanism therefor for uniformly moving said clamping members into clamping relationship, the screw-operating mechanism comprising a member operably engaging a plurality of such screw means to simultaneously operate such plurality of screw means.

70 3. Apparatus according to claim 2, in which

the screw-operating mechanism comprises a rack and a pinion driven thereby, the pinion being adapted to rotate the screw means whereby to move the clamping members into clamping relationship.

4. Apparatus according to claim 2, in which 5 the screw-operating mechanism comprises a worm gear and a worm wheel driven thereby, the worm wheel being adapted to coact with the screw means whereby to move the clamping members into clamping relationship. 10

5. Apparatus for handling materials comprising a platen, a frame adapted to be placed substantially around a load, and means for fastening the platen to the frame under tension, said means comprising a bent portion of the platen 15 near the outer edge thereof, and a clamping member adapted to engage the said bent portion while the clamping member is in an open position, said clamping member having its clamping cheek disposed angularly to the direction of 20 the tension to be imposed upon the platen and being movable outwardly to a clamping position, the bent portion of the platen and the said angular positioning of the clamping cheek affording 25 a restraint against slippage of the platen relatively to the clamping member while the latter is being moved outwardly to a clamping position.

6. Apparatus for handling materials, comprising a platen, a frame adapted to be placed substantially around a load, and means for fastening 30 the platen to the frame under substantially uniform tension, said means comprising outwardly movable clamping means adapted to yieldingly and uniformly engage a plurality of portions of 35 the platen and to impose a substantially uniform degree of tension on such portions of the platen relatively to each other while the clamping means are moving from an open to a closed position.

7. Apparatus for handling materials, comprising a platen, a frame adapted to be placed substantially around a load, and means for fastening the platen to the frame under substantially uniform tension, said means comprising a plurality of similar outwardly-extending bent portions 45 of the platen, a pair of clamping members adapted to uniformly engage the said bent portions, one of said clamping members being fixed relative to the load, the other clamping member being movable outwardly toward the said fixed member to bring the two into clamping engagement, said portions of the platen being yieldingly held adjacent the bends therein between said clamping members in a uniform and progressively tightening grip while the movable clamping member is being moved outwardly to its clamping position, whereby all slack is eliminated from the platen and a uniform tension established therein.

8. Apparatus for handling materials, comprising a platen, and a U-shaped frame having two substantially parallel sides, a closed end and an open end, said frame being adapted to be horizontally moved to a position extending substantially around a load, the parallel sides of the platen 65 and the corresponding parallel sides of the frame having coacting means for fastening the platen to the frame under tension.

9. Apparatus for handling materials, comprising a U-shaped frame adapted to be horizontally moved to a position extending substantially 70 around a load, said frame having a cross-member hinged to one of the sides of the frame at the open end thereof and adapted to bridge the open end of the frame, and means for operating 75

said cross-member from the closed end of the frame.

10. Apparatus according to claim 9, in which the cross-member is adapted to move by gravity to a bridging position when the frame is lowered to the floor.

11. Apparatus according to claim 9, in which a latch device on the frame is adapted to hold the cross-member in a substantially vertical position while the frame is in an elevated position and to automatically release said cross-member and permit it to move to a bridging position when the frame is lowered.

12. In the combination of apparatus for handling materials, comprising a platen, a frame, and clamping members carried by the frame for clamping a side of the platen to the corresponding side of the frame, screw means and operating mechanism therefor for moving the clamping members into clamping relationship, the screw-operating mechanism comprising an elongated worm gear meshing with and adapted to drive a plurality of worm wheels connected to the said screw means, the worm gear having driving gearing comprising a spur wheel and pinion, the spur wheel being adapted to be rotated to directly drive the worm gear, and the pinion being adapted to be rotated to drive the worm gear through the medium of the spur gear whereby to obtain a high clamping pressure between the clamping members.

13. A positioning device for aligning flexible upturned members in a substantially single plane, said device comprising a pair of elongated members hingedly connected at one end to permit lateral movement of said members, said device being adapted to be opened and closed and to be moved in a lengthwise direction to a position in which the members being aligned will extend upwardly between said elongated members.

14. Apparatus for handling materials comprising a platen for carrying a load and positioning means for holding a portion of the platen in position to be gripped by a conveying apparatus, the platen having a portion extending outwardly and upwardly from the side of the load, and the positioning means comprising an elongated member adapted to be horizontally moved into a position between the load and the upwardly-extending portion of the platen whereby to hold such portion in an upright position.

15. Apparatus for handling materials, comprising a load-carrying platen having a plurality of similar upturned portions spaced from a load to be carried and a frame having clamping members and being adapted to be moved horizontally to a position extending substantially around the load at a higher level than the ends of the said upturned portions, thence downwardly to a position adjacent the base of the load; a positioning device for aligning the upturned portions of the platen with the said clamping members, said device comprising a pair of elongated spacing members, adapted to engage the upturned portions of the platen therebetween with the upper ends of such portions extending above the top of such spacing members in substantial vertical alignment with the clamping members, one of the pair of spacing members being disposable between a load and the upturned members of the platen and the other spacing member being disposable along the outer sides of the upturned members, the pair of spacing members coacting with the load and a portion of the frame whereby, when the frame is moved horizontally to its

position about the load, the spacing members are urged together with the upturned portions of the platen held in alignment therebetween.

16. Apparatus according to claim 15, in which the spacing members are hingedly connected at one end and have means at the opposite ends adapted to assist in horizontal movement of the spacing members to their respective positions about the upturned members.

17. In apparatus of the character described, a platen clamping mechanism comprising an outwardly movable clamping element adapted to yieldingly engage a member to be clamped while said element is being moved toward its extreme outward clamping position, and means for moving said element to such position.

18. In apparatus of the character described, a platen clamping mechanism comprising an outwardly movable elongated clamping element adapted to uniformly engage a platen at a plurality of points, and means for simultaneously tightening the said element and moving it outwardly to an extreme outward position.

19. In apparatus of the character described, a mechanism for clamping a platen in said apparatus under tension, said mechanism comprising a pair of elongated clamping members disposed along a side of said apparatus for engaging a platen at a plurality of points and means for uniformly operating said clamping members, one of said members being movable outwardly to a closed position, and the cheeks of said members being angularly disposed relatively to the direction of the tension to be imposed upon the platen.

20. The method of fastening a platen in a frame under tension which comprises securing the platen, along one side thereof to one side of the frame, imposing a bend along the opposite side portion of the platen, bringing said bent portion into a substantially uniform yieldable engagement with an elongated clamping portion of the corresponding opposite side of the frame, and moving said clamping portion outwardly to its extreme outward tensioning position, at the same time progressively increasing the pressure present in the engagement of the bent portion of the platen and the clamping portion of the frame, whereby to clamp the platen to the frame and tension it therein.

21. The method of fastening a platen in a frame under substantially uniform tension which comprises yieldably engaging opposite side portions of the platen with outwardly movable clamping members on corresponding opposite sides of the frame, uniformly tightening said clamping members until the said side portions of the platen are unyieldingly held therebetween and uniformly moving said clamping members outwardly to an extreme tensioning position, the said tightening of the clamping members and the movement outwardly of said clamping members being progressively effected simultaneously or substantially so.

22. Apparatus for handling materials comprising a platen and a frame, the latter having clamping means on opposite sides thereof for clamping the platen to the frame under tension, said clamping means on one side of the frame comprising a fixed elongated clamping member having its clamping cheek disposed on the inner side thereof and angularly to the direction of the tension to be imposed upon the platen and a movable elongated clamping member disposed substantially parallel to said fixed clamping member and movable outwardly to a uniform clamp.

ing relationship with the said fixed member, the platen having a main portion, and side portions adapted to be engaged by said clamping means on corresponding sides of the frame, the dimension across the main portion of the platen between said side portions being smaller than the distance between the fixed clamping member on the one side of the frame and the engaged position of the cheeks of the clamping means on the other side of the frame, one of said side portions of the platen being adapted to be uniformly engaged by said movable and fixed clamping members and having a bend therein and a portion extending upwardly from said bend between and substantially parallel to the cheeks of said clamping members, the angularity of the said clamping members and the uniformity of the cooperation therebetween along substantially their entire length being such that while they are being tightened there exists a possibility of slippage of the platen therebetween and also a sufficient restraint against such slippage to impose a substantially uniform tension on said platen.

23. Apparatus according to claim 22, in which the angularly disposed clamping members and

an upwardly extending portion of the platen are provided on both corresponding sides of the frame and platen respectively.

24. Apparatus according to claim 9, in which the width of the frame and the length of the cross-member are adjustable to permit the handling of different sized loads.

25. In apparatus of the character described, a frame having means on opposite sides thereof for fastening a load supporting element thereinto under tension, said means on one side comprising a fixed outer clamping member and an outwardly movable inner clamping member adapted to coact therewith.

26. In apparatus of the character described, a frame having means on opposite sides thereof for fastening a load supporting element thereinto under tension, said means on one side comprising a fixed outer clamping member and an outwardly movable inner clamping member adapted to coact therewith, the cheeks of said clamping members being angularly disposed relatively to the direction of movement of the movable clamping member.

GEORGE H. PRIDE. 25
